UNITED STATES PATENT OFFICE.

WILLIAM BARTHOLOMEW, OF CHICAGO, ILLINOIS, ASSIGNOR TO TROY LAUNDRY MACHINERY COMPANY, LTD., OF CHICAGO, ILLINOIS, A CORPORATION OF NEW YORK.

SAFETY DEVICE FOR CENTRIFUGAL EXTRACTORS.

1,214,986.

Specification of Letters Patent.

Patented Feb. 6, 1917.

Application filed February 18, 1913. Serial No. 749,138.

To all whom it may concern:

Be it known that I, WILLIAM BARTHOLOMEW, a citizen of the United States, residing at Chicago, in the county of Cook and State of Illinois, have invented certain new and useful Improvements in Safety Devices for Centrifugal Extractors, of which the following is a specification.

My invention relates in general to laundry machinery, and more particularly to centrifugal extractors.

In the operation of centrifugal extractors numerous accidents have occurred to the operators by reason of the suction created within the rotating basket by the high speed of its revolution. In order to avoid such accidents it has heretofore been proposed to provide covers for preventing the operators from inserting their hands within the revolving baskets, and to interpose interlocking connections between such covers and the power-applying means, so that the covers must be closed before the power can be applied and the power disconnected before the covers can be raised. It is obvious however that such devices do not afford complete protection to the operators, inasmuch as the cover can be raised after the power has been disconnected but while the basket is still rotating by momentum at a dangerous speed.

The primary object of my invention is to provide a centrifugal extractor in which the cover will be automatically locked in closed position and will be automatically retained in closed position as long as the basket revolves.

A further object of my invention is to provide a centrifugal extractor in which the driving power can only be applied to rotate the basket when the cover is closed; in which the cover when closed will be automatically locked in such position, and in which it will be impossible to unlock the cover as long as the basket continues to revolve.

A still further object of my invention is to provide a cover for a centrifugal extractor with a latch which will, when the cover is closed, automatically lock the cover in such position, and to provide means for preventing the actuation of such latch to release

the cover as long as the basket continues to revolve.

A final object of my invention is to provide a centrifugal extractor, or a similar machine, with safety mechanism for protecting the operators from injury, which will be comparatively simple in construction and efficient in use.

My invention will be more fully described hereinafter with reference to the accompanying drawings, in which the same is illustrated as embodied in a convenient and practical form, and in which—

Figure 1 is a side elevation;

Fig. 2, a detail vertical section illustrating the relation between the cover and belt shifter;

Fig. 3, a plan view;

Fig. 4, an enlarged detail on line 4 4, Fig. 3;

Fig. 5, a rear elevational view; and

Fig. 6, a sectional detail on line 6 6, Fig. 5.

Similar reference characters are used to designate similar parts in the several figures of the drawings.

Reference letter A indicates the casing of a centrifugal extractor in which is inclosed the usual revolving basket *a*. B designates a suitable support for the casing A comprising standards and a base *b* adapted to be supported upon the floor. C designates a cover for closing the top of the casing, thereby preventing access to the inclosed basket. D designates a vertical spindle upon the upper end of which the basket is supported and to which power is applied for rotating the same and thereby imparting revolution to the basket. *d* designates a pulley secured concentrically around the spindle D which is engaged by a driving belt E.

The driving belt E extends around a pulley *E'* fixed upon a shaft *e'* suitably journaled at its ends in the vertical brackets *F'*, *F*² of a suitable supporting frame F. *E*² and *E*³ designate pulleys, one fixed to and the other loose upon the shaft *e'*. *e*² and *e*³ designate idler guide pulleys around which the belt E passes from the pulley *E'* to the pulley *d* on the spindle D.

G designates a belt shifter comprising a

reciprocating rod supported in the upper ends of the brackets F' and F^2 and provided with a handle g for reciprocating the same. g^2 and g^3 designate the guides carried by 5 the reciprocating rod of the belt shifter G and adapted to engage the power belt g' to shift the same from the tight to the loose pulley or vice versa.

I designates a brake for engaging the 10 pulley d on the spindle D so as to stop the rotation thereof, such brake being provided with a foot-actuated lever i .

The centrifugal extractor, and its coöperating parts above described, do not in themselves constitute my invention, but are herein disclosed in order that the construction and operation of my invention may be fully understood.

By reference to Fig. 2, it will be seen that 20 when the cover C is lifted into a substantially vertical position it will be held open by means of a gravity latch c' pivoted to the upper end f^2 of the bracket F^2 and adapted to extend through an opening c^2 in the cover 25 C adjacent the hinge c thereof. This construction is also shown in Fig. 6. It will be observed that when the cover is lifted it extends across the path of the reciprocating rod of the belt shifter G and thereby prevents the belt shifter from moving in a direction to shift the belt g' from the loose pulley E^2 to the tight pulley E^3 . Therefore power cannot be applied to rotate the basket when the cover is open. When the cover is 35 closed, which may occur only by lifting the gravity latch c' , the belt shifter may be moved to apply power to the spindle and in such position the inner end of the rod G overlies the cover adjacent the hinge c , as 40 shown in Fig. 3, thereby preventing the cover from being raised as long as the shifter is in position to apply power to the spindle.

H designates a vertical oscillatory shaft 45 journaled upon the frame F by means of a bracket H' at the lower end of the shaft, and a bracket H^2 projecting laterally from the upper end f^2 of the bracket F^2 , as will be seen by reference to Fig. 5. The handle h 50 is secured to the upper end of the shaft H for oscillating the latter. Rigidly secured to the lower end of the shaft H is a radially projecting lever K which at its free end extends adjacent the spindle D of the basket. 55 L designates a cam fixed to the spindle D and preferably in the form of an ellipse, which is located in the same horizontal plane as the free end of the lever K .

M designates an arm secured to the shaft 60 H adjacent its upper end and carrying within its outer end a spring actuated latch M' . The construction of this latch will be evident from Fig. 4, in which m^3 designates a spring surrounding the rod m^2 projecting

from the inner end of the latch, such spring 65 being interposed between the latch and the adjacent surface of the recess in the end of the arm M in which the latch is located. A stop pin m' projects upwardly from the latch M' through a slot m in the top wall 70 of the chamber in which the latch is located. N designates a crank arm secured at one end to the pivot rod n of the cover C , the rod n being rigidly secured to the cover, as shown in Fig. 6. When the cover is closed, the 75 crank arm N occupies a horizontal plane immediately above that of the latch M' .

O designates a spring secured at one end to the bracket H' , and its other end to a crank arm o rigidly secured to the shaft 80 H adjacent its lower end.

The manner of using and operation of my improved centrifugal extractor are as follows: Assuming that the parts are in the position shown in full lines in the drawings, 85 it will be seen that the power belt g' engages the tight pulley E^3 , thereby rotating the shaft e' and with it the pulley E' . The belt E is thereby driven and communicates motion, through its engagement with the 90 pulley d , to the spindle D and thence to the basket. The position of the belt shifter, as above explained, prevents the raising of the cover C , owing to the inner end of the reciprocating rod of the shifter overlying the 95 basket adjacent its hinge. The cover is also retained in its closed position by reason of the latch M' underlying the outer end of the crank arm N fixed to the cover C through the medium of the pivot rod n to which both 100 the cover and the crank arm are fixed. The latch M' is retained in position beneath the outer end of the crank arm N by reason of the spring O acting through the shaft H . The cover cannot, therefore, be raised unless 105 the shaft H is oscillated against the tension of the spring O so as to swing the latch M' from beneath the outer end of the crank arm N .

Such an oscillation of the shaft H is prevented during the rotation of the basket by 110 reason of the cam L fixed upon the spindle D which engages the free end of the lever K twice during each revolution of the spindle D . The rapid movement of the double cam L past the free end of the lever 115 K prevents such lever from being turned toward the spindle and consequently prevents the shaft H being rocked sufficiently to disengage the latch M' from beneath the free end of the crank arm N . The cover is 120 therefore retained in closed position as long as the power is applied to the basket by reason of the inner end of the belt shifter rod overlying the cover adjacent its hinge. When the belt shifter is actuated to disconnect the belt from the spindle, the cover is 125 retained closed by reason of the latch M' underlying the crank arm N , and it is im-

possible to disengage the latch from the crank arm as long as the basket continues to rotate at sufficient speed to be dangerous to the operator, owing to the rotation of the cam L relatively to the inner end of the lever K which prevents the oscillation of the shaft H sufficiently to disengage the latch from the crank arm on the cover.

After the basket has ceased to rotate, which may be facilitated by means of the brake I, pressure is applied to the handle h and the shaft H oscillated against the tension of the spring O and in a direction to remove the latch M' from beneath the crank arm N, such oscillation of the shaft being permitted by reason of the play between the inner end of the lever K and the portions of the cam L having the shorter radius. The cover may then be lifted into the position shown in Figs. 2 and 6 where it will be retained by the gravity latch c' in the path of the belt shifter.

After the clothes from which the water has been extracted have been removed from the basket and other clothes placed therein preparatory to having the water extracted from them, the gravity latch c' is lifted and the cover C closed. The closing of the cover causes the crank arm N to swing upwardly from the depending position which it occupies when the cover is open, past the latch M', which is beveled in an upward direction, to a position slightly above the latch so that the latter is projected by its actuating spring beneath the outer end of the crank arm. The cover is thereby automatically locked in closed position imminently upon its being closed. The belt shifter is then actuated which retains the cover in closed position as long as the belt is applied to the tight pulley. The rotation of the spindle then commences and through the cam L thereon co-operating with the free end of the lever K prevents the oscillation of the shaft H in a direction to disengage the latch M' from the crank arm N.

From the foregoing description it will be observed that I have invented an improved safety mechanism for centrifugal extractors, whereby the operators are protected from injury no matter how careless they may be. The cover must be closed before power can be applied to the basket and cannot be raised until the power has been disconnected. The cover is automatically further locked in closed position as soon as closed and retained locked in closed position as long as the basket continues to rotate, thereby preventing the lifting of the cover after the power has been disconnected from the basket but while it continues to revolve by momentum. Even after the rotation of the basket has so diminished as to permit the cover to be unlocked it is necessary to manually apply

power to the lock before the cover can be raised. It will therefore be seen that my invention fully safe-guards those who operate centrifugal extractors and avoids any liability of their injury no matter how careless they may be.

While I have illustrated and described my invention as embodied in a centrifugal extractor and have defined the same in the following claims with reference to such embodiment thereof, yet I do not wish thereby to be understood as restricting the application of my invention to centrifugal extractors, but intend thereby to protect it for whatever uses it may be adapted and in whatever forms it may be capable of practical embodiment.

I claim:

1. In a centrifugal extractor, the combination with a rotary basket, a casing within which the basket is inclosed, a cover for said casing, means for rotating said basket, a manually operative latch for locking said cover closed, a plurality of projections rotated by said means for rotating the basket, and a movable member connected with said latch and extending in the path of rotation of said projections when the latch is in unlocked position, whereby the operation of said latch to unlock the cover is prevented during the rotation of said basket.

2. In a centrifugal extractor, the combination with a rotary basket, a casing within which the basket is inclosed, a cover for said casing, means for rotating said basket, a latch for automatically locking said cover closed, means for manually operating said latch to unlock the cover, a plurality of projections rotated by said means for rotating the basket, and a movable member connected with said latch and extending in the path of rotation of said projections when the latch is in unlocked position, whereby the operation of said latch to unlock the cover is prevented during the rotation of said basket.

3. In a centrifugal extractor, the combination with a rotary basket, a casing within which said basket is inclosed, a cover for said casing, power transmitting mechanism for rotating said basket, a latch automatically locking said cover closed, means for manually operating said latch to unlock the cover, a plurality of projections rotated by said power transmitting mechanism, a movable member connected with said latch and extending into the path of rotation of said projections when the latch is in unlocked position, whereby the operation of said latch to unlock the cover during the rotation of the basket is prevented.

4. In a centrifugal extractor, the combination with a rotary basket, a casing within which said basket is inclosed, a cover for said casing, a spindle on which said basket

is supported and by which it is rotated, means for rotating said spindle, a latch for automatically locking said cover when closed in closed position, means for manually operating said latch to unlock the cover, and mechanism for preventing the actuation of said manual means to unlock the cover comprising a member projecting eccentrically from and rigidly connected with said 10 spindle below said basket.

5. In a centrifugal extractor, the combination with a rotary basket, a casing within which said basket is inclosed, a cover for said casing, power transmitting mechanism for rotating said basket, a latch for locking said cover closed, a lever operatively connected with said latch for controlling the movement thereof, and a plurality of elements actuated by the power transmitting 15 mechanism and having a path of movement intersecting the path of said lever, whereby the movement of said lever necessary to permit the disengagement of the latch from the cover is prevented during the rotation 20 of the basket.

6. In a centrifugal extractor, the combination with a rotary basket, a casing within which said basket is inclosed, a cover for said casing, power transmitting mechanism for 30 rotating said basket, a latch for locking said cover closed, a lever operatively connected with said latch for controlling the movement thereof, and a projection fixed to and revolving with a rotary member of the power transmitting mechanism and having a path of movement intersecting the path of said lever, whereby the movement of said lever necessary to permit the disengagement 35 of the latch from the cover is prevented during the rotation of the basket.

7. In a centrifugal extractor, the combination with a rotary basket, a casing within which said basket is inclosed, a cover for said casing, power transmitting mechanism for 45 rotating said basket, a latch for locking said cover closed, an oscillatory shaft for operating said latch to lock and unlock the cover, a lever operatively connected with said shaft for controlling the unlocking movement of said latch, and a projection actuated by the power transmitting mechanism having a path of movement intersecting 50 the path of said lever.

8. In a centrifugal extractor, the combination with a rotary basket, a casing within which said basket is inclosed, a cover for said casing, power transmitting mechanism for rotating said basket, a latch for locking said cover closed, a spring for retaining 55 said latch in locking engagement with said cover, a handle for moving said latch into unlocked position, a lever operatively connected with said latch, and a cam rotated by the power transmitting mechanism 60

and having a path of movement intersecting 65 the path of said lever, whereby said lever cannot be moved in a direction to permit the unlocking of said latch during the rotation of said basket.

9. In a centrifugal extractor, the combination with a rotary basket, a casing within which said basket is inclosed, a cover for said basket, a latch for locking said cover closed, an oscillatory shaft for operating said latch to lock and unlock the cover, a 70 spring for retaining said shaft in position to retain said latch in locking position, a handle for oscillating said shaft in a direction to disengage the latch from said cover, a lever operatively connected with said 75 shaft, power transmitting mechanism for rotating said basket, and a plurality of projecting elements rotated by the power transmitting mechanism and having a path of movement intersecting the path of said lever, whereby said lever cannot be moved in a direction to permit said shaft to oscillate in a direction to disengage said latch 80 from the cover.

10. In a centrifugal extractor, the combination with a rotary basket, a casing within which said basket is inclosed, a cover for said basket, a latch for locking said cover closed, an oscillatory shaft for operating said latch to lock and unlock the cover, a spring for retaining said shaft in position to retain said latch in locking position, a handle for oscillating said shaft in a direction to disengage the latch from said cover, a lever operatively connected with said 90 shaft, a spindle upon which said basket is supported and by which it is rotated, and a cam projecting radially from said spindle and having a path of movement intersecting 95 the path of said lever, whereby said lever cannot be moved in a direction to permit the oscillation of said shaft to unlock the latch during the rotation of the basket.

11. In a centrifugal extractor, the combination with a rotary basket, a casing within which said basket is closed, a cover for said casing, power transmitting mechanism for rotating said basket, a vertical spindle upon the upper end of which said basket is mounted, means for controlling the connection of said power transmitting mechanism with said basket, means for preventing the opening of the cover while power is applied to the basket, a latch for automatically locking the cover when closed, and means for preventing the movement of said latch to unlock the cover during the rotation of the basket comprising a member projecting eccentrically from and rigidly connected with said spindle below said basket.

12. In a centrifugal extractor, the combination with a rotary basket, of a casing within which said basket is inclosed, a cover

for said casing, and means for preventing the opening of said cover during the rotation of said basket comprising a plurality of projections rotated during the rotation 5 of said basket, and a movable member extending into the path of rotation of said projections when the cover is opened, whereby the successive contacts of said projections with said member prevent the move-

ment of the member in a direction to permit the opening of the cover during the rotation of the basket.

In testimony whereof, I have subscribed my name.

WILLIAM BARTHOLOMEW.
